UNITED STATES PATENT OFFICE

161,493

LADY'S STOCKING

William Nebel, Charlotte, N. C.

Application July 2, 1949, Serial No. 3,669

Term of patent 14 years

(Cl. D47—7)

To all whom it may concern:

Be it known that I, William Nebel, a citizen of the United States of America, residing at Charlotte, in the county of Mecklenburg, State of North Carolina, have invented a new, original, and ornamental Design for a Lady's Stocking, of which the following is a specification, reference being had to the accompanying drawings, forming a part thereof.

I claim:

The ornamental design for a lady's stocking, substantially as shown.

WILLIAM NEBEL.
